UNITED STATES PATENT OFFICE

CHARLES R. CRANE, 2d, AND ROY H. ZINKIL, OF CHICAGO, ILLINOIS, ASSIGNORS TO CRANE CO., OF CHICAGO, ILLINOIS, A CORPORATION OF ILLINOIS

DESIGN FOR A SINK

Application filed December 24, 1928. Serial No. 29,396. Term of patent 14 years.

To all whom it may concern:

Be it known that we, CHARLES R. CRANE, 2d, and Roy H. ZINKIL, citizens of the United States, residing at Chicago, in the county of Cook and State of Illinois, respectively, have invented a new, original, and ornamental Design for a Sink, of which the following is a specification, reference being had to the accompanying drawing, forming part thereof.

In the drawing:

Fig. 1 is a perspective view of a sink, showing our new design, and Fig. 2 is a plan view thereof.

We claim:

The ornamental design for a sink, as shown.

CHARLES R. CRANE, II.
ROY H. ZINKIL.
